UNITED STATES PATENT OFFICE

MERVIN CHESTER HUFFMAN, OF CLAREMONT, NEW HAMPSHIRE, ASSIGNOR TO
SULLIVAN MACHINERY COMPANY, A CORPORATION OF MASSACHUSETTS

TOOL RETAINER

Application filed June 26, 1930. Serial No. 464,088.

This invention relates to tool retainers and more particularly but not exclusively to improved tool retainers for rock drills or similar hammer tools.

5 An object of this invention is to provide an improved tool retainer. Another object is to provide an improved retainer for the working implement of a hammer rock drill or similar tools. Another object is to provide an 10 improved means for holding the retaining element in its operative position and in its inoperative position. A further object is to provide an improved retainer for the working implement of a rock drill or similar 15 hammer tool, wherein improved resilient means is provided for mounting the retaining element in a novel manner on the drill. Yet another object is to provide an improved 20 tool retainer of a rugged and simple design well adapted to withstand hard usage and which can be readily assembled and disassembled. These and other objects and advantages of this invention will however hereinafter more fully appear.

25 In the accompanying drawings there is shown for purposes of illustration one form which the invention may assume in practice. In these drawings,—

Fig. 1 is an elevational view of the forward 30 portion of a hammer rock drill with which the illustrative form of the improved tool retaining means is associated;

Fig. 2 is a central longitudinally extending sectional view taken substantially on line 35 2—2 of Fig. 1;

Fig. 3 is a view taken substantially on line 3—3 of Fig. 2, the inoperative position of the retaining element being indicated by dotted lines; and

40 Fig. 4 is a detail sectional view taken on line 4—4 of Fig. 2.

In this illustrative embodiment of the invention the improved retaining means is shown associated with a rock drill of the hammer type although it is obvious that the same may be embodied in various other types of tools wherein a reciprocatory working implement is employed. In the construction shown the rock drill, generally designated 1, 45 includes a front chuck housing 2 in which

there is rotatably mounted a chuck sleeve 3 threadedly connected at 4 to a usual chuck 5. This chuck is provided with a polygonal socket 6 which receives the hexagonal shank 7 of a usual rock drill steel 8. Formed integral with this drill is a suitable abutment herein in the form of a collar 9. The forward wall of the chuck housing is bored at 10 to permit the insertion of the drill shank within the chuck. Contained in the drill cylinder 11 is a usual hammer piston having a forwardly projecting striking bar 12 which is adapted to transmit impact blows to the shank of the drill steel in a well known manner. As the particular type of rock drill employed does not enter into this invention, and the improved retaining means may be incorporated in tools of various other types, further description of the same is thought to be unnecessary.

Now referring to the improved tool retaining means, it will be noted that formed integral with the chuck housing 2 is a longitudinally arranged hollow casing 13 having a bore 14 arranged parallel with and offset from the axial line of the drill. This offset casing projects forwardly from the front end of the chuck housing, and mounted within the bore therein is a cylindrical body 15 of a retaining element 16. The body of this retaining element in its cooperation with bore 14 forms a hinge about which the retaining element is adapted to swing. This retaining element is provided with a hook-shaped stop piece 17 having an open sided slot 18 which, when the retaining element is in its operative position, embraces the drill steel body. The stop piece is recessed at 19 and the collar on the drill steel is adapted to project within this recess when the steel is in its extreme forward working position. It will thus be seen that the stop piece is so hinged as to swing into and out of the path of the collar 9 on the drill steel.

45 In this improved construction the retaining element is mounted in a novel manner on the drill and this improved mounting comprises a reduced cylindrical portion herein in the form of a stud 20 projecting rearwardly from and formed integral with the

100

cylindrical body 15 of the retaining element. This stud projects rearwardly from the retaining element body through an aperture 21 in the transverse rear wall of the offset casing 13. A suitable detent lock is employed for maintaining the retaining element in its operative and inoperative positions and herein comprises an angular portion 22 on the stud, herein of hexagonal cross-section, fitting a correspondingly shaped opening at 23 in a lock washer 24 surrounding the stud 20. This washer is provided at its forward surface with projecting teeth 25 having curved outer faces which engage arcuate notches or grooves formed in the rear face of the offset casing 13. These teeth are yieldably maintained in locking engagement with the grooves by means of a coil spring 26 encircling stud 20 and interposed between the lock washer 24 and a nut 27 threaded on the rear end of the stud. It will thus be seen that when the parts are in the position shown in Fig. 2, the retaining element is locked in its operative position with the stop piece 16 projecting into the path of the drill steel collar. When it is desired to release the drill steel from the chuck this may be accomplished simply by swinging the retaining element laterally from the full line position shown in Fig. 3 to the dotted line position, thereby moving the stop piece out of the path of the drill steel collar. The drill steel can then be freely withdrawn from the chuck. The retaining element is held in its inoperative position by the lock washer 24 held by the coil spring 26 in frictional engagement with the rear end wall of the offset casing 13. It also will be noted that when the retaining element is swung laterally about its hinge the angular portion 22 on the stud 20 causes the lock washer 24 to be rotated into its released position, the connection between stud and lock washer at the same time permitting sliding movement of the lock washer relative to the stud.

While there is in this application specifically described one form which this invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a tool of the character described, the combination with a working element having an abutment and a front head having a longitudinal bore adapted to receive the shank of the working implement, of a casing on the side of the front head having a bore parallel with and offset from the axial line of the tool, a retaining element having a transversely swingable stop piece adapted to move into and out of the path of the abutment on the

working implement and a cylindrical body fitting said offset bore to form a hinge about which the stop piece is swingable, means for yieldably mounting said cylindrical body of said retaining element in said offset bore including a stud secured to said body and a co-operating spring encircling said stud, and means for locking said retaining element in its operative retaining position including a locking element carried on said stud and movable relative thereto into and out of its locking position.

2. In a tool of the character described, the combination with a working element having an abutment and a front head having a longitudinal bore adapted to receive the shank of the working implement, of a casing on the side of the front head having a bore parallel with and offset from the axial line of the tool, a retaining element having a transversely swingable stop piece adapted to move into and out of the path of the abutment on the working implement and a cylindrical body fitting said offset bore to form a hinge about which the stop piece is swingable, means for yieldably mounting said cylindrical body of said retaining element in said offset bore, and means for locking said retaining element in its operative retaining position including a spring pressed locking element having teeth cooperating with notches formed in the end wall of said offset casing and movable relative to said retaining element into and out of its locking position.

3. In a tool of the character described, the combination with a working element having an abutment and a front head having a longitudinal bore adapted to receive the shank of the working implement, of a casing on the side of the front head having a bore parallel with and offset from the axial line of the tool, a retaining element having a transversely swingable stop piece adapted to move into and out of the path of the abutment on the working implement and a cylindrical body fitting said offset bore to form a hinge about which the stop piece is swingable, means for yieldably mounting said cylindrical body of said retaining element in said offset bore, and means for locking said retaining element in its operative retaining position including a locking element connected to said retaining element to rotate on swinging of said rotating element about its pivot and movable relative thereto into and out of its locking position.

4. In a tool of the character described, the combination with a working element having an abutment and a front head having a longitudinal bore adapted to receive the shank of the working implement, of a casing on the side of the front head having a bore parallel with and offset from the axial line of the

tool, a retaining element having a transversely swingable stop piece adapted to move into and out of the path of the abutment on the working implement and a cylindrical body fitting said offset bore to form a hinge about which the stop piece is swingable, means for yieldably mounting said cylindrical body of said retaining element in said offset bore including a stud secured to and projecting from said cylindrical portion rearwardly through an opening in the end wall of said offset casing and a cooperating spring encircling said stud, and means for locking said retaining element in its operative retaining position including a locking element carried on said stud and rotatable with said stud on swinging of said element about its hinge, said locking element being movable relative to said stud into and out of its locking position.

5. In a tool of the character described, the combination with a working element having an abutment and a front head having a longitudinal bore adapted to receive the shank of the working implement, of a casing on the side of the front head having a bore parallel with and offset from the axial line of the tool, a retaining element having a transversely swingable stop piece adapted to move into and out of the path of the abutment on the working implement and a cylindrical body fitting said offset bore to form a hinge about which the stop piece is swingable, means for yieldably mounting said cylindrical body of said retaining element in said offset bore including a stud secured to and projecting from said cylindrical portion rearwardly through an opening in the end wall of said offset casing and a cooperating spring encircling said stud, and means for locking said retaining element in its operative retaining position including a locking element slidably mounted on said stud, said spring acting on said locking element for maintaining the latter in its operative locking position.

6. In a tool of the character described, the combination with a working element having an abutment and a front head having a longitudinal bore adapted to receive the shank of the working implement, of a casing on the side of the front head having a bore parallel with and offset from the axial line of the tool, a retaining element having a transversely swingable stop piece adapted to move into and out of the path of the abutment on the working implement and a cylindrical body fitting said offset bore to form a hinge about which the stop piece is swingable, means for yieldably mounting said cylindrical body of said retaining element in said offset bore including a stud secured to and projecting from said cylindrical portion rearwardly through an opening in the end wall of said offset casing and a cooperating spring encircling said stud, and means for locking said retaining element in its operative retaining position.

position including a locking element slidably mounted on said stud and connected to said stud to rotate therewith upon swinging of said retaining element about its head, the connection between said stud and locking element permitting relative sliding movement therebetween. 70

7. In a tool of the character described, the combination with a working element having an abutment and a front head having a longitudinal bore adapted to receive the shank of the working implement, of a casing on the side of the front head having a bore parallel with and offset from the axial line of the tool, a retaining element having a transversely swingable stop piece adapted to move into and out of the path of the abutment on the working implement and a cylindrical body fitting said offset bore to form a hinge about which the stop piece is swingable, means for yieldably mounting said cylindrical body of said retaining element in said offset bore including a stud secured to and projecting from said cylindrical portion rearwardly through an opening in the end wall of said offset casing and a cooperating spring encircling said stud, and means for locking said retaining element in its operative retaining position including a locking element having a polygonal opening therethrough and fitting a corresponding polygonal portion on said stud and having sliding movement relative to the latter, swinging of said retaining element about its pivot causing rotative movement of said locking element.

In testimony whereof I affix my signature.
MERVIN CHESTER HUFFMAN.
